UNITED STATES PATENT OFFICE.

CHARLES ESCHWEI, OF NEW YORK, N. Y.

ELECTRIC CUT-OUT.

SPECIFICATION forming part of Letters Patent No. 354,466, dated December 14, 1886.

Application filed August 14, 1886. Serial No. 210,884. (No model.)

To all whom it may concern:

Be it known that I, CHARLES ESCHWEI, of the city, county, and State of New York, have invented certain new and useful Improvements in Electric Cut-Outs, of which the following is a specification.

The invention relates to certain new and useful improvements in automatic cut-outs used on electric lights for the purpose of cutting out one or a series of lamps, in case the carbon in the lamp has been consumed or any other part of the lamp is out of order.

The invention consists in a glass block provided with grooves for receiving the line-wires, 15 sockets connected with the line and lamp wires, cups between the sockets, bridge-pieces having pins fitting in the sockets, and fuses secured on the bridge-pieces, all as will be fully described and set forth hereinafter, and finally 20 pointed out in the claims.

In the accompanying drawings, Figure 1 is a plan view of my improved automatic cut-out, the same being shown open. Fig. 2 is a longitudinal section on the line $x-x$, Fig. 1. 25 Fig. 3 is a cross-sectional view on the line $y-y$, Fig. 2. Fig. 4 is a plan view of one of the bridge-pieces.

Similar letters of reference indicate corresponding parts.

30 The block A is made of glass or any other insulating material, and is provided with a hinged-top, B. Said block A is provided with two longitudinal grooves, C C', for the positive and negative wires $a a'$, which are held by 35 suitable binding-screws. The positive wire a is connected by the wire b with a socket, D, in that portion of the block A between the grooves C C'. At the opposite end the negative wire a' is connected by the wire b' with the socket 40 D'. In the middle part of that portion of the block between the grooves two sockets, E and E', are provided, which are connected with the positive and negative wires $c c'$ of the lamp F. Between the sockets D E and D' E' the caps 45 G are sunk in the surface of that part of the block A between the grooves C C'. The bridge-piece H is made of glass and provided with spring-pins I, which can be passed into the sockets D E, respectively, which pins are connected with metal pieces J in the bottom edge 50

of the bridge-pieces H, and which metal pieces J are connected by a highly-fusible wire, K, which passes down into a cap, G. Another bridge, H, having a pin, I', plate J', and fusible plug K, is provided at the opposite end, the 55 pins I' being passed into the sockets D' E', respectively. Both poles of the light are thus connected with the pins of the bridge-pieces, and the current passes from the lamp through the fusible pieces K K', within the caps G, 60 through the pins I I' to the line-wires $a a'$.

Ordinarily the hinged cover B is swung on the block A so as to cover the wires $a a'$, and the bridge-pieces are introduced through the slots M in the hinged cover B. In case the 65 carbons burn out or the lamp breaks, or any other accident occurs, the tension in the circuit of the lamp increases to such an extent that the fuses melt, and the lamp is thus cut out automatically. If one lamp is cut out it does 70 not interfere with the other lamps on the same line-wire.

In place of connecting the block A with a single lamp, it may be provided in the same manner with a line on which a series of lights 75 are provided. In case any fuse has been destroyed, the bridge-piece can be withdrawn and a new fuse-piece can be inserted in the bridge in a short time.

Having thus described my invention, I claim 80 as new and desire to secure by Letters Patent—

1. The combination, with the electric conducting-wires, of a block of insulating material provided with grooves through which said wires are passed, sockets in said blocks connected with the lamp-wires, bridge-pieces having pins for connecting the main and lamp wires, and fusible wires on said bridge-pieces, which fusible wires are in electrical connection with the main and lamp wires, substantially as shown and described. 85 90

2. The combination, with a block of insulating material having two grooves, of connecting-screws in each groove for making connection with the main line-wires, sockets connected with the said screws, sockets connected with the lamp-wires, bridge-pieces having pins fitting in the sockets, and fuses on the bridge-pieces, which fuses are connected with the pins, substantially as described. 95 100

3. The combination, with a block having grooves, of sockets connected with the main and lamp wires, bridge-pieces having pins, metal plates connected with the pins, and fusible pieces connected to the plates below the bridge-pieces, substantially as set forth.

4. The combination, with a block having grooves for the line-wires, of sockets in said block connected with the line and lamp wires, bridge-pieces for connecting the sockets, fuses

on the bridge-pieces, and a slotted hinged cover on the block, substantially as set forth.

In testimony that I claim the foregoing as my invention I have signed my name in presence of two subscribing witnesses.

CHARLES ESCHWEI.
